(57) **CLAIM**

The ornamental design for an elastomeric clamp, as shown.

DESCRIPTION

FIG. 1 is a front perspective view of an elastomeric clamp, showing our new design with a strap portion in a first position;

FIG. 2 is a front side elevation view thereof;

FIG. 3 is a back side elevation view thereof;

FIG. 4 is a left side elevation view thereof;

FIG. 5 is a right side elevation view thereof;

FIG. 6 is a top plan view thereof; and

FIG. 7 is a bottom plan view thereof;

FIG. 8 is a front perspective view of the elastomeric clamp, showing our new design with the strap portion in a second position;

FIG. 9 is a front side elevation view thereof;

FIG. 10 is a back side elevation view thereof;

FIG. 11 is a left side elevation view thereof;

FIG. 12 is a right side elevation view thereof;

FIG. 13 is a top plan view thereof; and,

FIG. 14 is a bottom plan view thereof.
